UNITED STATES PATENT OFFICE.

KARL RUDOLPH, OF POESSNECK, GERMANY.

COIN-FREED APPARATUS FOR ADMINISTERING ELECTRICITY.

SPECIFICATION forming part of Letters Patent No. 578,526, dated March 9, 1897.

Application filed March 18, 1896. Serial No. 583,836. (No model.)

To all whom it may concern:

Be it known that I, KARL RUDOLPH, a subject of the Grand Duke of Saxe-Weimer, and a resident of Poessneck, in the Duchy of Saxe-Meiningen, German Empire, have invented certain new and useful Improvements in Coin-Freed Apparatus for Administering Electricity, of which the following is a specification.

10 The present invention refers to a coin-freed apparatus for administering electricity, in which the person making use of the same can increase or diminish the power of the current as desired. The power of the current attained 15 can easily be read from a scale provided for that purpose. One of the handles of the device is rigidly connected with an induction-coil, so that the latter can be made to cover more or less entirely the primary coil. The 20 more fully it covers the same, and this can be measured from any suitable scale, the more powerful the induced current will be. The primary current-circuit is closed only during a certain period of time by a coin 25 dropped in the machine, a clockwork being put in motion thereby, which again breaks the circuit after a certain time.

The invention is illustrated in the accompanying drawings.

30 Figure 1 is a plan view thereof, the cover being partly broken away. Fig. 2 is a longitudinal section on a vertical plane.

The mechanism of the apparatus is located in a closed box and works as follows: The 35 coin falls through the slot in the cover upon the guiding-groove K and slides down upon the flexible springs e, arranged over the oval opening u. The weight of the coin separates the springs, whereby the lever m, operated 40 by the spring, is moved. One of the extremities of the lever n is raised. The other presses down the straight arm of the lever o, and the pin v, fixed to the latter, plunges in the mercury-contact p. In such a manner the circuit of the current generated by the dry battery 45 is closed, so that the current passes through the primary coil g of the induction apparatus and creates an induction-current in the secondary coil f. Said current leads 50 to the spherical handles a a, which are taken

hold of by the person wishing to use the machine. One of the handles, that to the right, is rigidly connected with the induction-coil in such a manner that it can be more or less drawn over the primary coil. How far it is 55 drawn over can be read from the scale on the cover at the side of the slot through which the shaft of the ball passes. The spiral springs d serve to bring back the coil to its original position.

60 The electrifying lasts about one-half minute and after that the current-circuit is broken. A wheel h' is rotated by a clockwork which revolves once in one minute and has two notches on its periphery, into which the hook-shaped 65 end of the lever o engages. When the straight end of the lever o is depressed by the coin dropped in the slot, as described, the hook releases the wheel, so that the wheel h' can rotate. The hook slides then upon the periphery of the wheel h', and after the coin has fallen off or has been pushed forward by the bolt i it engages the second notch of the wheel h' after half a minute. The apparatus 70 then stops.

A bell r can be connected with the apparatus which can be put in or out of circuit by suitable contacts.

I claim—

1. A coin-freed electrifying-machine, comprising two springs arranged below the slot through which the coin is dropped, a lever mechanism operated by the movement of one of the springs under the weight of the coin, and connections for controlling and operating the electric circuit, substantially as described.

2. In combination, the springs e, e adapted to receive the coin, the wheel h' having notches, the lever o, the electric contact p, w controlled thereby, and the levers n and m between the lever o and the spring-contacts and bearing on one of said contacts, substantially as described.

In witness whereof I have hereunto set my hand in presence of two witnesses.

K. RUDOLPH.

Witnesses:

RICHARD PESER,
F. C. HERM. KAROL.
